UNITED STATES PATENT OFFICE

136,076

DESIGN FOR A SHOE

William Birenbaum, Haverhill, Mass.

Application October 13, 1941, Serial No. 103,750

Term of patent 3½ years

To all whom it may concern:

Be it known that I, William Birenbaum, a citizen of the United States and a resident of Haverhill, in the county of Essex and Commonwealth of Massachusetts, have invented a new, original, and ornamental Design for a Shoe, of which the following is a specification, reference being had to the accompanying drawing, forming part thereof, in which,

Fig. 1 is a plan view of a shoe showing my new design, and

Fig. 2 is a side elevational view, the opposite side presenting substantially the same appearance except for the absence of the buckle. The

essential features of the design are shown in full lines.

The essential feature of my design consists in strap-like portions for the forepart and quarter of a sandal upper arranged as shown, each portion presenting the appearance of leaves overlapping in solid formation with adjacent corresponding edges disposed in substantially parallel relation.

I claim:

The ornamental design for a shoe, substantially as shown and described.

WILLIAM BIRENBAUM.
